UNITED STATES PATENT OFFICE.

CLARENCE KNOL, OF GRAND RAPIDS, MICHIGAN.

COLLAPSIBLE BARREL.

1,321,317.

Specification of Letters Patent.

Patented Nov. 11, 1919.

Application filed January 22, 1918. Serial No. 213,139.

To all whom it may concern:

Be it known that I, CLARENCE KNOL, a citizen of the United States of America, residing at Grand Rapids, in the county of Kent and State of Michigan, have invented certain new and useful Improvements in Collapsible Barrels; and I do hereby declare the following to be a full, clear, and exact description of the invention, such as will enable others skilled in the art to which it appertains to make and use the same.

This invention relates to a collapsible receptacle, particularly a barrel, though it is to be understood that the invention is applicable to various types of receptacles other than barrels. It is a primary object and purpose of the invention to make a receptacle of connected collapsible sections which are adapted to nest one within the other when not in use, means being provided to hold the sections in extended position for completion of the receptacle when it is to be used. A further object and purpose of the invention consists in the provision of a novel joint between the sections, such that when the receptacle is fully extended the joint is substantially proof against leaking, the receptacle thus being adapted to hold liquids as well as solid materials. The construction by which I attain these ends is fully illustrated in the accompanying drawing, in which,

Figure 1 is a partial perspective and sectional view of a collapsible barrel made in accordance with my invention.

Fig. 2 is a plan view thereof.

Fig. 3 is a plan view showing the sections of the barrel nesting one within the other, this being the position that they take when the barrel is collapsed, and

Fig. 4 is an enlarged sectional view illustrative of the joint between the sections.

Like reference characters refer to like parts in the different views of the drawing.

In construction a central section 1 is used, constructed preferably, of two parts 2 which have inwardly extending abutting flanges 3, suitably connected by rivets or other permanent connections. A plurality of additional sections 4 progressively decreasing in diameter are located above and below the central section 1, and are of a width to be received and nested within the parts 2 of the central section when the barrel is collapsed. Suitable upper and lower ends 5

and 6 may be used to close the end sections of the barrel, though any desired type of cover may be used as seems best.

Each of the sections 4 interlocks with an adjacent section, each lower section being provided at its lower edge with an inwardly turned U-shaped bend 7 extending entirely around the section, in which a U-shaped gasket 8 is located, while at its upper edge it is formed with an outwardly and downwardly turned U-shaped bend 9, the outer leg of which terminates in an enlarged head 10 adapted to enter between the sides of the gasket 8 of the section next above. The lower edge of the lower part 2 of the central section is likewise provided with an inturned U-shaped portion 7 for attachment of the adjacent section 4 thereto. This construction is the same for the upper sections of the barrel except that the sections are reversed, as will be obvious.

A plurality of bars 11 are hinged, as indicated at 12, adjacent both the upper and lower edges of the central section 1, the upper and lower ends of said bars being fashioned into rods 13 which are screw-threaded and are adapted to enter socket members 14 fixed on the uppermost and lowermost sections 4 of the barrel. A nut 15 threads on to each rod 13 and is adapted to associate with a socket member 14, as shown, it being evident that by proper adjustment the sections may be fully and completely extended and drawn apart so that the parts 10 are brought tightly into engagement with the gaskets 8, a firm and practically water proof barrel being produced in this manner.

When the barrel is collapsed the various sections nest together, and the bars 11, having been disconnected from the socket members 14, may turn across the ends 5 and 6 of the barrel, on which suitable clips 16, adapted to receive the rods 13, are secured, normally preventing outward movement of the various sections.

The construction is relatively simple and may be made entirely of metal. For shipping purposes the barrel may be collapsed to small compass and is held in collapsible position by engagement of the rods 13 with the clips 16. When in position for service the rigidity of the structure and tightness of the joints is controlled by the nuts 15 which may be tightened as desired. It is of course ap-

parent that other types of receptacles may be made in accordance with the structure of this invention such, for instance, as either the upper or lower half of the construction shown in Fig. 1, while different shapes and heights of sections may be used. In practice, the sections 4 adjacent the central section abut against the flanges 3 and are stopped from passing too far inwardly on collapsing of the receptacle. On outward movement of the sections the joints automatically interlock, and the barrel is very quickly and easily set up or collapsed.

I claim:

15 1. A collapsible receptacle comprised of a central section, a plurality of upper and lower sections adjustably connected to each other and to the central section so as to be extended to form the sides of the receptacle or retracted to nest one within the other and all within the central section, a plurality of braces hingedly connected at the upper and lower edges of the central section, and at the outer sides thereof, means on the 20 uppermost and lowermost sections with which said upper and lower braces are adapted to detachably connect, and means on the braces coacting with said means on the sections for extending the sections and 25 making tight joints between the adjacent sections, substantially as described.

2. A collapsible receptacle comprising a lower section formed at its upper edge with an inwardly and downwardly turned U-shaped annular bend, a plurality of sections of progressively diminishing size located above the lower section, all except the uppermost section being similarly formed at their upper edges, and all at their lower 35 edges being formed with an outwardly and upwardly turned U-shaped annular bend

adapted to detachably interlock with the bend at the upper edge of the next lower section, a plurality of braces hingedly connected at their lower ends to the upper part 45 of said lower section and at the outer sides thereof, socket members connected to the uppermost section in which said braces are adapted to seat at their upper ends, and nuts on each brace, one above and the other below 50 its socket member for extending the sections and drawing them tightly into engagement with each other.

3. A construction containing the elements in combination claimed in claim 4, combined 55 with a top to close the upper end of the uppermost section, and clips on said top adapted to detachably receive said braces when the receptacle is collapsed and the braces turned over said top, substantially as 60 described.

4. In combination, a central section provided with an annular inwardly extending flange midway between its upper and lower edges, a series of collapsible sections connected together and to said central section above and below said flange, detachable interlocking U-shaped bends at upper and lower edges of said sections adapted to interlock when the sections are extended, rigid 70 braces hingedly connected at the upper and lower edges of the central section, and at the outer sides thereof, means on the uppermost and lowermost sections of the receptacle adapted to have detachable connection 75 with said braces, and means on the braces coacting with said means on the sections to extend the sections and draw the interlocking parts thereof into close engagement, substantially as described. 80

In testimony whereof I affix my signature.
CLARENCE KNOL.
